[57] CLAIM

The ornamental design for the a pier lifter for elevating
building footings, as shown and described.

DESCRIPTION

FIG. 1 is a perspective view of a pier lifter for elevating
building footings showing my new design;

FIG. 2 is a top plan view thereof;

FIG. 3 is a left side elevational view thereof with the
right side being a mirror image;

FIG. 4 is a bottom plan view thereof;

FIG. 5 is a front elevational view thereof; and,

FIG. 6 is a rear elevational view thereof.

The broken line showing of a pipe shaft is for illustrative
purposes only and forms no part of the claimed
design.

FIG. 1.

FIG. 2.

FIG. 3.

FIG. 4.

FIG. 5.

FIG. 6.
